UNITED STATES PATENT OFFICE.

CLAUDE C. SALMONS AND JAMES MAHONEY, OF WEST PHILADELPHIA, PENNSYLVANIA.

COMBINED CLAMP AND FASTENER.

1,352,919.

Specification of Letters Patent. Patented Sept. 14, 1920.

Application filed September 14, 1917. Serial No. 191,403.

To all whom it may concern:

Be it known that we, CLAUDE C. SALMONS and JAMES MAHONEY, citizens of the United States, residing at West Philadelphia, in the county of Philadelphia and State of Pennsylvania, have invented new and useful Improvements in Combined Clamps and Fasteners, of which the following is a specification.

10 This invention relates to a combined clamp and fastener for use in securing various parts or elements to hollow tiles, walls, blocks or slabs, etc., in building constructions, such as for fastening chair rails, picture moldings or the like to hollow walls, or soap cups or the like to marble slabs, etc., or for fastening any article to a surface which requires the surface to be pierced and a holder to be applied to carry the fastening member, and particularly where it is impossible or impracticable to reach the inner face of the wall or surface to which the article is to be fastened, such as the inner face of one side of a hollow wall.

25 One object of the invention is to provide a combined clamp and fastener in which the clamp, to which the fastening member is applied, is adapted to be readily, conveniently, firmly and expeditiously applied to a hollow wall or other surface.

30 A further object of the invention is to provide a device of the character described which is adapted for general fastening purposes of the character defined, and which embodies a novel and efficient form of holding clamp to which the screw or other fastening member is applied.

The invention consists of the features of construction, combination and arrangement 40 of parts, hereinafter fully described and claimed, reference being had to the accompanying drawing, in which:—

45 Figure 1 is a vertical section through a hollow tile wall, showing the device as used for fastening a chair rail or molding in place.

Fig. 2 is a vertical longitudinal section through the device.

50 Fig. 3 is a horizontal longitudinal section thereof.

Fig. 4 is a view similar to Fig. 2 showing the device as arranged for introduction into the wall.

Fig. 5 is a view of a modified form of tumbler adapted for special use.

In carrying the invention into practice, 55 we provide a combined clamp and fastener comprising a body member 1 and a tumbler or retaining member 2, forming a clamp, and adapted to be employed in conjunction with a fastening 3, such as a screw, of a suitable type. The body member 1 is preferably formed of bendable sheet metal, and is provided at its side edges with a pair of parallel upturned flanges 4. These flanges 60 4 have forward extensions 5 and rearward extensions 6. The forward extensions 5 form a pair of bendable clamping arms or fingers of some suitable length, which are employed for a purpose hereinafter described, while the rearward extensions 6 65 form supports for the tumbler or retaining member 2 and project a comparatively short distance beyond the inner or rear end 70 of the body 1.

The tumbler or retaining member 2 comprises a solid bar, of oblong rectangular form, which is formed or provided on its side edges, at a point between its transverse center and one of its ends, with pivot members or projections 8 which engage pivot openings 9 formed in the support 6, whereby said tumbler or retaining member is pivotally mounted for swinging movement, from a position, such as shown in Fig. 4, parallel 85 with the body 1 and flanges 4, to a position, such as shown in Figs. 1, 2 and 3. In the first named position, the upper or shorter end of the tumbler 2 folds or extends over upon the body 1 and within the groove or 90 recess formed by the flanges 4, while in the second named position the tumbler extends vertically between the supports 6 and is held from lateral movements thereby.

The tumbler 2 is provided, in the form of 95 the invention shown in Figs. 1 to 4, inclusive, with a threaded opening 10 to receive the fastening member 3, which may be, as shown, a machine screw of suitable length for the intended purpose. In the slightly modified 100

form of the invention shown in Fig. 5 the bar 2 is shown as provided with an opening 11 threaded to receive a wood screw 12, designed for use in securing certain objects which can not be secured by means of a machine screw. It will, of course, be understood that while a screw type of fastening is herein disclosed, any other suitable type of fastening capable of being employed for the purpose may be adopted. In Fig. 5 the bar is provided with a longitudinal slot 11' making the side walls of the opening 11 springy so as to lightly grip the thread of the screw and hold the screw from working loose.

The device is designed particularly for use in fastening articles to or upon one surface of a wall or other support in which it is necessary to pierce the wall or support for the purpose, and particularly for fastening articles to hollow tiles or other walls where it is impossible to secure access to the inner side of the wall in order to place a fastening in position. In the present disclosure, we have shown the device as employed for fastening a picture molding 13 to the outer face of a hollow wall composed of divided wall sections 14 and 15 having an intermediate space 16 therebetween. In applying the combined clamp and fastener for use a hole 17 is formed in one or the other of the walls 14 and 15, say the wall surface 14, between its outer and inner faces, and, the screw 3 or 12 being removed from the threaded opening in the tumbler or retainer bar 2, said bar is then swung to lie in a plane parallel with the body 1 and flanges 4, as shown in Fig. 4, after which the bar and adjacent portions of the clamp are forced longitudinally through the opening 17 until the bar 2 passes beyond the inner face of the wall 14. In this operation of introducing the device the bar 2 will be held in the position stated by the walls of the opening 17 until it passes the inner face of the wall 14, whereupon, being no longer supported, it will be caused to tilt or swing to a vertical position, parallel with the inner face of the wall 14. This tilting motion, it will be obvious, is due to the eccentric pivoting of said bar to the supports 6, whereby its longer or heavier end is adapted to drop by gravity when the device is fully inserted. The bar 2 will then act as a retainer to hold the device from withdrawal from the opening 17, and may be brought to lie snugly against the inner surface of the wall 14 by an outward pull upon the arms or fingers 5. These arms or fingers are then bent laterally in opposite directions as best seen in Fig. 3, to lie against the outer face of the wall 14, whereupon the device will be clamped in position upon the wall. The molding 13 or other object to be held is then placed in position against the wall and over the bent portions of

the arms 5 and the screw 3 or 12 inserted and engaged with openings 10 or 11 in the bar 2 and screwed up, thereby connecting the molding with the clamp or retaining bar and clamping both firmly against relative movement. It will, of course, be understood that either a machine screw or a wood screw may be used, according to the nature or character of the article which is to be applied and secured in position. It will also be understood that the bent portions of the arms 5 may be trimmed down as required so that they will be concealed behind the objects secured, thus making a neat and attractive finish and entirely concealing the fastening means, with the exception of the head of the fastening screw, 80 from view. If desired, the head of the fastening screw may be concealed from view by countersinking it and otherwise concealing it by known methods in the article secured, thus making the fastening entirely invisible. 85 It will be evident that when so applied the combined clamp and fastener will be rigidly held in position and will form a firm and suitable support for the molding, chair railing or other article secured to the face of the 90 wall, and that by the construction and use of the device in the manner set forth articles of various kinds may be secured to hollow tile walls with great ease and convenience and without injury to the wall.

Our improved fastening may also be employed for securing soap cups and various other articles to walls, marble slabs, and the like, or for fastening any article to a surface which requires the surface to be pierced and a holder to be applied to carry the fastening member. The pivot tumbler adapts the device to be readily introduced and, by automatically tilting to an operative position, provides a clamping member for engaging one side of an otherwise inaccessible surface of a wall or slab, so that the holder and clamping member may be quickly and efficiently employed in place and held firmly against extraction.

Having thus fully described our invention, we claim:

1. As an article of manufacture, a fastening device comprising a body formed of a pair of flat strips of a pliable material, a cross piece formed integrally with the lower edges of the strips and holding the same in spaced parallel relation, said cross piece connecting said strips at a point intermediate their ends whereby to provide long and short sections extending to either side thereof, a tumble bolt eccentrically pivoted to the short sections of the strips and having an opening therein, and a fastening member adapted to be extended through the body for engagement with the opening in said tumble bolt, the construction being such that the long sections of the strips may be bent laterally in

opposite directions and severed at any point along their length beyond said cross piece whereby to form retaining members of any required length.

5 2. A bolt comprising a body, retaining means at one end of the body, a bolt eccentrically pivoted at the opposite end of the body, said bolt having a threaded opening

and a slot intersecting the same and forming spring walls, and a screw adapted for engagement with said threaded opening. 10

In testimony whereof we affix our signatures.

CLAUDE C. SALMONS.
JAMES MAHONEY.
